UNITED STATES PATENT OFFICE.

GRANVILLE H. GRAY, OF SANTA ANA, CALIFORNIA, ASSIGNOR TO BROCK GLASS COMPANY, OF SANTA ANA, CALIFORNIA, A CORPORATION OF CALIFORNIA.

DESIGN FOR A DRAWER HANDLE.

Application filed July 18, 1925. Serial No. 14,139. Term of patent 14 years.

To all whom it may concern:

Be it known that I, GRANVILLE H. GRAY, a citizen of the United States, residing at Santa Ana, in the county of Orange and State of California, have invented a new, original, and ornamental Design for Drawer Handle, of which the following is a specification, reference being had to the accompanying drawing, forming part thereof.

Figure 1 is a front elevation of the handle showing my new design;

Figure 2 is a plan;

Figure 3 is a vertical cross-section taken on the line 3-3 of Figure 1.

I claim:

The ornamental design for a drawer handle as shown.

GRANVILLE H. GRAY.
